(57) **CLAIM**

The ornamental design for a cigar lighter, as shown and described.

DESCRIPTION

FIG. 1 is a front elevational view of a first embodiment of the cigar lighter showing my new design;

FIG. 2 is a rear elevational view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a front elevational view thereof showing retractable parts extended; and

FIG. 8 is a rear elevational view thereof showing retractable parts extended;

FIG. 9 is a front elevational view of a second embodiment of the cigar lighter showing my new design;

FIG. 10 is a rear elevational view thereof;

FIG. 11 is a top plan view thereof;

FIG. 12 is a bottom plan view thereof;

FIG. 13 is a right side elevational view thereof;

FIG. 14 is a left side elevational view thereof;

FIG. 15 is a front elevational view thereof showing retractable parts extended; and,

FIG. 16 is a rear elevational view thereof showing retractable parts extended.

Any broken line illustration of environmental structure in the drawing is not part of the design sought to be patented.
